UNITED STATES PATENT OFFICE.

GILES M. TURNER, OF MADISON, WISCONSIN, ASSIGNOR TO HOLM'S MACHINE MANUFACTURING COMPANY, OF SPARTA, MICHIGAN, A CORPORATION OF MICHIGAN.

MEANS FOR SUPPORTING AND DRIVING ELECTRIC GENERATORS.

1,030,354.

Specification of Letters Patent. Patented June 25, 1912.

Application filed August 28, 1911. Serial No. 646,459.

To all whom it may concern:

Be it known that I, GILES M. TURNER, a citizen of the United States, residing at Madison, in the county of Dane and State 5 of Wisconsin, have invented certain new and useful Improvements in Means for Supporting and Driving Electric Generators, of which the following is a specification.

- 10 When a magneto or other current-generator is used to supply ignition current to an internal-combustion engine, it has been customarily mounted upon some portion of the bed or engine framework, and has been driven 15 by means of a belt or gear connection with the crank shaft or some secondary shaft of the engine. Difficulty has been experienced, however, in so locating and driving the generator, by reason of interference with the 20 fly wheel, pulley, drive belt or the like, particularly in the case of stationary engines which are usually supplied with a drive pulley located at either end of the crank shaft as specified by the purchaser.
- 25 The objects of my invention are to obviate the difficulty above alluded to, and to eliminate the expense incident to a special support and drive. These objects I attain 30 by utilizing either end of the crank shaft or some other suitable shaft of the engine as a means for supporting and directly driving the armature of the generator, and by freely suspending the field structure upon the armature journals.

- 35 In the accompanying drawings, Figure 1 is a diagrammatic view illustrating the application of my invention to a stationary engine. Fig. 2 is an end elevation and Fig. 3 a side elevation of the magneto supported 40 in accordance with my invention. Fig. 4 is a diagrammatic representation of the circuit-breaker of the magneto.

The invention is applicable to automobile, marine, and stationary engines, but is herein shown, by way of example, as used in connection with a stationary motor.

1 designates an end of an engine shaft, as, for instance, the crank shaft. The magneto may be of any common or preferred 50 construction, that herein shown comprising an armature 2, an armature shaft 3, a housing 4 having bearings 5 and 6 for the armature shaft, and field magnets 7 secured to the housing 4. The armature shaft 3 is attached to the shaft 1 in a suitable manner,

as by providing said shaft 3 with a socket 8 to receive the end of the shaft 1. Any preferred means, as, for instance, a set screw 9, may be used to secure the socket 8 upon the shaft 1. The magneto framework or housing 4 with the attached field structure is supported or suspended upon the armature shaft or journals, and is herein illustrated in inverted position.

When intended for use with an engine 65 employing jump-spark ignition, means may be provided for shifting the breaker lever 10 with relation to the breaker cam 11. Since the cam is driven from the armature shaft, and the circuit breaker lever is attached to the housing 4, it will be seen that the spark may be advanced or retarded by adjusting the suspended structure about the axis of the armature. Herein I have shown 70 an arm 12 secured to a portion of the suspended structure and having a portion 13 upon which a weight 14 is adjustably mounted.

15 is a set screw for locking the weight 14 in the desired position. It will be seen 80 that the arm 12 and the weight 14 constitute means for shifting the center of gravity of the magneto, and that the housing 4 may be adjusted about the axis of the armature by altering the center of gravity of the 85 suspended structure. Such shifting means may be omitted in the case of engines equipped for make-and-break ignition:

It will be apparent that the magneto may be placed at either end of the crank shaft, 90 depending upon the location specified for the drive pulley by the purchaser; and that there is no supporting device or drive connection to interfere with the drive belt or the operative parts of the engine.

I claim as my invention:

1. The combination of an internal combustion engine and a current-generator comprising an armature with its journals and a field structure, one of the armature journals being affixed to one end of the engine crank shaft, and the field structure being suspended from the armature journals.

2. The combination of an internal combustion engine; a magneto comprising a 100 housing, an armature rotatably mounted in the housing, and a field magnet attached to the housing; and means for fixing the armature to and supporting it by one end of the engine crank shaft, the housing and 110

field magnet being suspended in inverted position.

3. The combination of an internal-combustion engine and a current-generator, the latter comprising a portion fixed to and wholly supported by the engine crank-shaft, and the remainder of the generator being freely suspended from said shaft-supported portion, the suspended portion having a 10 relatively shiftable mass attached thereto.

4. The combination of an internal-combustion engine and a current-generator, the latter comprising a portion fixed to and wholly supported by the engine crank-shaft, 15 and the remainder of the generator being freely suspended from said shaft-supported portion, a member attached to said suspended portion and located below the axis

of the crank shaft, and a weight adjustably attached to said member.

5. The combination of an internal-combustion engine, a magneto comprising an armature attached to the engine crank shaft, a housing supported by the armature, a circuit-breaker lever carried by the housing, 25 a circuit-breaker cam having a driving connection with the armature, and a field magnet attached to the housing; and means for adjusting the housing about the axis of the engine crank shaft.

In testimony whereof I hereunto affix my signature in the presence of two witnesses.

GILES M. TURNER.
